UNITED STATES PATENT OFFICE.

HERMAN NEUMAN, OF PAINESDALE, MICHIGAN.

CRIB.

SPECIFICATION forming part of Letters Patent No. 710,115, dated September 30, 1902.

Application filed March 24, 1902. Serial No. 99,689. (No model.)

To all whom it may concern:

Be it known that I, HERMAN NEUMAN, a citizen of the United States, residing at Painesdale, in the county of Houghton and State of Michigan, have invented certain new and useful Improvements in Cribs; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in cribs to be used in sinking shafts in quicksand and other strata. It has for its object a construction which shall be simple and economical and durable and efficient in use.

20 Improved details in the construction and arrangement of the several parts of my invention will be apparent from the detailed description hereinafter when read in connection with the accompanying drawings, forming part hereof, and the appended claims.

The invention embodies the idea of forming a crib with outstanding ledges, the upper faces of which are horizontal, or substantially so, and the lower faces or sides of which are inclined or beveled, so that the ledges will offer resistance to the lifting or forcing out of the crib by upward pressure and at the same time permit its sinking in quicksand with greater facility and ease than would otherwise be the case by entering the sand at an angle and pushing the same laterally.

35 In the drawings, Figure 1 is a perspective view. Fig. 2 is a cross-section.

40 Referring to the drawings, 4 designates the

base of my improved crib, comprising side timbers 5 and end timbers 6. A metal lining 7 projects below the side and end timbers, its object being to cut into the sand and clear the way for the crib. The base is 45 braced by cross-beams 5^a and 5^b. The walls of the crib are indicated at 8, the timbers 9, forming the same, being joined at the corners in any suitable manner and braced by cross-beams 10. The outer ends of each of the 50 timbers 9 are beveled, as indicated at 11, forming a ledge 12 on the next timber below. The same construction is followed on each side of the crib.

Having thus described my invention, what 55 is claimed as new, and desired to be secured by Letters Patent, is—

1. A crib having outstanding upwardly-presented ledges on its outer walls, substantially as shown and described. 60

2. A crib comprising superposed frames having upwardly-presented horizontal ledges on the outside edges thereof, substantially as shown and described.

3. A crib comprising a series of superposed 65 horizontal beams, the upper surface of each beam being of greater width than the lower surface of the adjoining upper beam, forming earth-engaging ledges on the outside of the crib. 70

4. A crib having outstanding upwardly-presented ledges on its outer walls, and a cutting edge at its base, substantially as shown and described.

In testimony whereof I affix my signature 75 in presence of two witnesses.

HERMAN NEUMAN.
